UNITED STATES PATENT OFFICE

2,584,049

CAN OPENER

Jean O. Reinecke, Oak Park, Ill., assignor to the
United States of America as represented by the
Secretary of War

Application January 23, 1947, Serial No. 723,863

2 Claims. (Cl. 30—15.5)

1

This invention is directed to can openers of the general type comprising a base plate, a rotatably mounted cutter, a feed wheel or driver for the can to be opened, means for shifting the position of the feed wheel to permit the can to be placed in operative position with respect to the rotatably mounted cutter and means for rotating the feed wheel.

In can openers of this general type, it is customary to employ a yieldable pressure member disposed adjacent the feed wheel to press against the upper end of a can and force the latter into frictional engagement with the feed wheel. These pressure members, usually operated by means of a compression spring, have been rather complex in structure and their construction and installation constitute a comparatively large percentage of the cost of manufacture of the can opener as a whole.

An object of the present invention is to greatly simplify the structure for causing the frictional contact between the feed wheel and cans, and yet maintain or improve the simplicity and reliability of operation of this part of the can opener.

A further object of the invention resides in the construction of a simplified pressure plate which may be readily installed with a minimum of operational steps and without the aid of expensive machinery.

Other objects and advantages of the invention will be apparent from the following description when taken in connection with the accompanying drawings in which:

Figure 1 is a rear elevational view of a complete can opener embodying the present invention;

Figure 2 is a side elevational view thereof;

Figure 3 is a plan view of the can opener with parts broken away;

Figure 4 is a fragmentary front elevational view of the upper portion of the can opener;

Figure 5 is a vertical sectional view of the upper portion of the opener as shown in Figure 4, and

Figures 6 and 7 are elevational views of the arm employed for shifting the position of the feed wheel and the crank arm for rotating the feed wheel, respectively.

Referring to the drawings in greater detail, and particularly to Figures 1 and 2, the numeral 1 indicates an elongated base plate of channel formation adapted to be clamped to the edge of a table or the like. To this end a fixed clamping member 2 is mounted on the inside of the channel adjacent the lower end thereof, and a mov-

able clamping member 3 is threaded to a flanged bushing 4 fixed to the lower end of the base plate. A pivoted handle 5 is secured to the lower end of the movable clamping member 3 for operating the same from time to time as desired.

The rotatable cutter is indicated by the numeral 6 and is mounted on a portion 7 of the base plate on the front face thereof as clearly indicated in Figures 2, 4, and 5. Immediately below the cutter is a feed wheel 8 fixed to a rotatable shaft 9 which is eccentrically mounted in a cylindrical bushing or hub 10 which is oscillatable by a lever 11 so as to lower the feed wheel when a can is being placed in the machine and for thereafter raising the feed wheel to properly clamp the can in position for the cutting operation. A crank arm 12 is fixed to the shaft 9 for rotating the feed wheel 8 and thereby feed the upper end of the can against the cutter 6.

20 The foregoing features of the can opener and their arrangement are all well known in the art and therefore it is deemed unnecessary to describe them more specifically. But, as hereinbefore stated, this type of can opener necessitates the use of a pressure plate or foot for maintaining the can in proper feedings relationship to the feed wheel, and the pressure foot or plate of the present invention will now be described in detail.

25 The pressure plate is indicated by the numeral 13 and is provided with downward extensions having offset portions intermediate their ends and terminating in horizontal portions forming pressure feet 14 and 15 for engaging the upper edge of a can at opposite sides of the cutter 6. The body of the plate 13 is of substantially rectangular formation and is provided with a plurality of protuberances 16 adapted to space the body of the pressure plate from the base plate and thereby reduce friction between the parts when the plate 13 is moved relative to the base plate.

Both the pressure plate 13 and the base plate 1 are provided with vertically extending rectangular openings 17 which substantially register when the pressure plate is assembled with the base plate and the upper and lower edges of these openings are each provided with a stud 18. Disposed within the openings 17 is a compression spring 19 having its lower end engaged over the studs on the lower edges of the openings 17 and its upper end engaged over the studs 18 on the upper edges of these openings; a washer 20 being interposed between the upper end of the spring and the upper edges of the openings.

55 As will be noted from an inspection of Figures

1 and 4, the base plate is provided with a pair of rectangular openings 21 and the feet 14 and 15 of the pressure plate, as heretofore referred to, extend through those openings and are positioned at opposite sides of the cutter 6.

In assembling this novel part of the can opener, it is only necessary to bring the plate 13 into position with the rounded protuberances 16 in engagement with the back of the base plate 1 and with the openings 17 in substantial registration as indicated. Thereafter, the washer 20 may be placed in position over the upper studs 18 and the spring 19 compressed and inserted in position over the respective pairs of studs 18. The device is now ready for operation.

From the foregoing description and the attached drawings, it will be noted that I have devised a simplified pressure device for can openers which is free from lateral projections other than the pressure feet themselves, that it comprises only a plate, a spring and a washer, and that these parts may be easily and quickly mounted upon the main frame of the can opener without the use of bolts, screws, rivets, etc., and thus avoiding the time and labor involved in the use of such fastening means.

In accordance with the patent statutes I have described what I now consider to be the preferred form of the invention but various changes may be made in the details of construction without departing from the spirit of the invention, and it is intended that all such details be included within the scope of the appended claims.

I claim:

1. A can opener including a base plate provided with a pair of spaced openings, a rotary cutter, a feed wheel shiftable with respect to the cutter, a pressure plate mounted for rectilinear sliding movement against one side of the base plate, said pressure plate provided with downward extensions having offset portions passing through said pair of openings in the base plate, said extensions at their lower ends having hori-

zontal portions forming pressure feet for engaging the can being opened, said base plate and pressure plate being provided with registering openings, studs on the upper and lower edges of the registering openings, and a coil spring mounted in the registering openings and engaged over the studs to force the pressure plate toward the feed wheel.

2. A can opener including a base plate provided with a pair of spaced openings, a rotary cutter, a feed wheel shiftable with respect to the cutter, a pressure plate mounted for rectilinear sliding movement against one side of the base plate, said pressure plate provided with downward extensions having offset portions passing through said pair of openings in the base plate, said extensions at their lower ends having horizontal portions forming pressure feet for engaging the can being opened, anti-friction protuberances on the pressure plate for engagement with the base plate, said base plate and pressure plate being provided with registering openings, studs on the upper and lower edges of the registering openings, and a coil spring mounted in the registering openings and engaged over the studs to force the pressure plate toward the feed wheel.

JEAN O. REINECKE.
